UNITED STATES PATENT OFFICE.

JAMES W. RAMSDELL, OF HIGHLAND PARK, MICHIGAN.

DESIGN FOR A DRINKING-FOUNTAIN.

52,244.

Specification for Design.

Patented July 30, 1918.

Application filed November 19, 1917. Serial No. 202,884. Term of patent 14 years.

To all whom it may concern:

Be it known that I, JAMES W. RAMSDELL, a citizen of the United States, residing at Highland Park, in the county of Wayne and State of Michigan, have invented a new, original, and ornamental Design for a Drinking-Fountain, of which the following is a specification, reference being had to the accompanying drawings, forming part thereof.

I claim:

The ornamental design for a drinking fountain, as shown.

JAMES W. RAMSDELL.
